CLAIM

The ornamental design for an egg cracker, as shown and described.

DESCRIPTION

FIG. 1 is an upper perspective view of an exemplary container that may be used in connection with an egg cracker;

FIG. 2 is an upper perspective view of an egg cracker disposed in the exemplary container shown in FIG. 1;

FIG. 3 is an upper front perspective view of the egg cracker;

FIG. 4 is an upper rear perspective view of the egg cracker;

FIG. 5 is a lower front perspective view of the egg cracker;

FIG. 6 is a front view of the egg cracker;

FIG. 7 is a rear view of the egg cracker;

FIG. 8 is a left side view of the egg cracker;

FIG. 9 is a right side view of the egg cracker;

FIG. 10 is a top view of the egg cracker; and,

FIG. 11 is a bottom view of the egg cracker.

The broken lines shown in the figures are for illustrative purposes only and form no part of the claimed design.
